UNITED STATES PATENT OFFICE.

RUSSELL HANDY, OF MANVILLE, RHODE ISLAND.

LOOM FOR WEAVING DOUBLE PILED FABRICS.

SPECIFICATION forming part of Letters Patent No. 374,064, dated November 29, 1887.

Application filed September 15, 1885. Serial No. 177,132. (No model.)

To all whom it may concern:

Be it known that I, RUSSELL HANDY, of Manville, in the county of Providence and State of Rhode Island, have invented certain new and useful Improvements in Looms for Weaving Double Piled Fabrics, of which the following is a full, clear, and exact description, reference being had to the accompanying drawings, forming a part of this specification.

This invention has reference to the class of looms in which is woven double piled fabric—that is to say, a fabric consisting of two backs of interwoven fabric with pile-threads extending from one fabric to the other, which pile-threads are afterward cut, so as to form two separate sheets of velvet, velveteen, or other piled fabric.

The invention consists in the peculiar and novel construction of the mechanism by which the delivery of the pile warp to the harnesses is regulated and the pile-take-up device is controlled, and of the novel constructions of parts, as will be more fully set forth hereinafter.

Piled fabric is usually woven with a back from which a large number of pile-threads project to form a velvety surface, such as is the case in silk, cotton, and other velvet, and in velvet carpets. The velvet surface is formed by weaving a large number of loops into the back or fabric and then cutting these loops to form the soft velvet surface. Recently two sheets of this fabric have been woven simultaneously in a special loom, the pile extending from one back or fabric to the other, so that when the woven fabric has been split into two sheets by cutting the pile with a knife two sheets of velvet are produced.

The present invention refers to looms for weaving the double pile fabric.

Figure 1 is a side view of part of a loom, showing the mechanism for delivering and the device for taking up the pile warp and the mechanism co-operating therewith. Fig. 2 is an enlarged view of the pile-warp rod and the devices for operating the same. Fig. 3 is a view, partly in section, of the star and hand wheel by which the let-off mechanism controlling the delivery of the pile warp is operated. Fig. 4 is a sectional view of the hand-wheel, shown in connection with the star-wheel, taken on line 4 4, Fig. 3.

In the drawings, A is the pile-warp beam. B is the warp-beam from which the warp for the upper fabric is delivered. C is the warp-beam for the lower fabric or back. D are the harnesses by which the warp-threads are sprung. E is the breast-beam, and F is the lay, all suitably mounted in the loom frame, shown in portion.

The warp for the pile passes from the pile-beam A over the tension-roller a, which is mounted in a pair of swinging arms, a⁶, hinged to the loom-frame, and only one of which is shown, the fellow arm being in line therewith on the other side of the frame. This roller is a heavy metal roller and maintains the tension on the pile warp, which passes about roller a, as shown, and thence around the roller a' and over the roller a², whereby the delivery of the pile warp is limited to the rotation of the rolls a' and a², in a manner well known in this construction of warp-delivery rollers. The rolls a' and a² are each provided at the remote end with a fixed gear-wheel, J. These gears intermesh and cause the connected rolls to rotate oppositely at the same speed in letting off the yarn. The pile warp passes from the roller a² down under the pile-warp rod G, and thence to the heddle or harness by which the pile warp is sprung to enter the upper and lower fabric and is interwoven with the same by the filling-threads. The warp from the beams B and C is delivered to the harnesses in the usual manner.

H is a hand-wheel provided on its inner face with the boss h. This hand-wheel H is secured to the crank-shaft I by a spline, s, so that while it must rotate with the crank-shaft it can be drawn out longitudinally upon the shaft against the pressure of the spiral spring i. The boss h has a cavity or notch, t, formed on one side, in the center of which a pin, h', is placed. This pin enters one of the slots in the star-wheel k, which is secured to the shaft K, at each revolution of the shaft I and hand-wheel H.

The star-wheel k is provided with five slots and five concaved faces between the slots, which faces form segments of a circle equal to the diameter of the boss h, so that during the revolution of the boss h the star-wheel is firmly locked by the contact of one of the five faces against the circumference of the boss h until the cavity t reaches the star-wheel, when the

pin h' in the center of the cavity, which pin projects slightly beyond the periphery of the boss, enters one of the slots of the star-wheel k and turns the same one-fifth of a revolution, 5 the points on the star-wheel entering the cavity. As soon as this partial rotation of the star-wheel is accomplished, the same is again firmly held against rotation by one of the faces bearing against the periphery of the boss h . 10 By drawing the hand-wheel H outward against the spring i the star-wheel can be disengaged from the pin h' on the boss h , so as to permit the movement of the warp-delivery mechanism, which is necessary in adjusting the tension 15 on the pile warp.

To the shaft K , to which the star-wheel k is secured, is also secured a bevel-gear, v , which gears into and communicates its motion to the bevel-gear k' on the vertical shaft L , the upper end of which shaft L is provided with a worm, w , gearing into and rotating the worm-gear l , secured to the shaft of the roller a' .

It will be apparent that for each revolution of the shaft I by means of the star-wheel the 25 bevel-gears, the shafts K L , and the worm-gear l the rollers a' a^2 will be rotated a fixed distance, and that the length of pile warp delivered will be equal to the motion of the peripheries of the rollers a' a^2 , and also that the rollers a' a^2 will be firmly held against rotation as long as one of the faces of the star-wheel k bears against the periphery of the boss h .

To facilitate the turning of the shaft L when the hand-wheel H is drawn out and the tension 35 of the pile warp is to be regulated, the hand-wheel l' is secured to the shaft L , as shown in Fig. 1.

On the vertical shaft L , below the hand-wheel l' , is secured the beveled gear g , gearing 40 into the beveled gear g' , placed on a loosely-mounted horizontal shaft, r , on which the star-cam g^2 is secured. The proportions of the gears between the star-wheel k and the star-cam g^2 are such that both will make one-fifth of a 45 revolution and simultaneously. The star-cam g^2 has five concavities, in each of which the roller g^3 , journaled on the trip-lever g^4 , can firmly rest during the time the star-wheel k is locked against rotation. At each partial 50 rotation of the star-cam g^2 the roller g^3 , and with it the lever g^4 , is raised. The lever g^4 is provided on its outer end with a hook, g^5 , or equivalent means for securing the tension-spring g^6 , which is also secured to the tilt-lever g^7 , on the 55 opposite end of which the pile-rod G is secured, as is shown in Fig. 2 on an enlarged scale. Two sets of the devices shown in Fig. 2 are used on one loom—one set located near each end of the loom—and the pile-rod G extends over the whole width of the pile warp.

The pile-warp rod G , together with the immediately-connected parts for vibrating the rod, I term the "pile-take-up device," since by the action of said parts the slack pile-thread 60 is taken up as delivered by the pile-let-off apparatus above described.

The operations of these devices in connection with the operation of the loom are as follows: The shaft I makes one revolution to each reciprocation of the shuttles and turns the 70 star-wheel k one-fifth of a revolution, which motion is communicated to the roller a' and roller a^2 , whereby the pile warp is delivered to the pile-rod G , which at the same instant is depressed, and, bearing on the pile warp, takes 75 up the slack therein and delivers the same to the harnesses to form the interwoven pile-threads, which constitute the pile of the fabric.

The mechanism for operating the lay, the shuttles, and the harnesses are not shown. 80 They are of the old and well-known form, and form no part of this invention.

Having thus described my invention, I claim as new and desire to secure by Letters Patent—

1. The combination, with the intermittent motion mechanism consisting of a shaft provided with a hand-wheel formed with a notch or cavity and adapted to slide longitudinally thereon and to rotate therewith, a fixed pin on said hand-wheel within the notch or cavity, and a star-wheel engaging said wheel and pin and mounted on an adjacent shaft, which is provided with a bevel gear-wheel, of a pile-warp-take-up device provided with a gear-wheel, a pile-warp-let-off apparatus provided with a gear-wheel, a rotary shaft provided with a bevel gear-wheel in mesh with the bevel-gear of said intermittent-motion mechanism, and having a gear-wheel in mesh with said gear-wheel of the pile-warp-take-up device, and provided with a worm in mesh with the gear-wheel of said pile-warp-let-off apparatus, substantially as herein described. 90

2. The combination, with an intermittent motion mechanism provided with a gear-wheel, substantially as described, of a pile-warp-take-up device provided with a gear-wheel for driving the same, a pile-warp-let-off apparatus consisting of a pile-beam and intergeared delivery-rolls and a swinging tension-roller, one of said delivery-rolls provided with a gear-wheel, a connection intermediate of said intermittent-motion mechanism, said take-up and said let-off motions, and comprising a rotary shaft provided with fixed gears in mesh with the respective gear-wheels of said intermittent and take-up motions, respectively, and having a worm in mesh with the gear-wheel of said delivery-roller, substantially as herein described. 100

3. The combination of the crank-shaft, a hand-wheel sliding longitudinally over a spline on said shaft, a spring mounted on said shaft and engaging the hand-wheel, a boss on said wheel provided with a transverse notch on the periphery thereof, a fixed pin disposed partially within said notch, a rotary shaft adjacent to said wheel, and a star-wheel keyed thereon, said star-wheel engaging the periphery of said hub and the notch and pin, whereby the motion of the crank-shaft may rotate at intervals 115 of the star-wheel, and whereby the hand-wheel 120

may be moved to disengage said star-wheel, substantially as described.

4. The combination of a rotary shaft and means for intermittently actuating the same, 5 a loosely-mounted shaft geared to said rotary shaft and actuated thereby, a star-cam fixed on said loosely-mounted shaft, a trip-lever engaged by said star-cam, a tilt-lever and the pile-rod attached thereto, and a connection between said trip and tilt levers, whereby the intermittent rotation of the rotary shaft may control the star-cam, and thereby vibrate the take-up pile-rod, substantially as described.
5. The combination of the crank-shaft, a 15 hand-wheel sliding on said shaft, splined thereto, a boss upon said wheel provided with a transverse notch, a fixed pin lying partially within the length of said notch, a turnable shaft adjacent to said wheel, and a star-wheel 20 and a bevel-gear keyed thereon, a rotary shaft provided with a bevel-gear in mesh with said first bevel, a pinion-wheel keyed on said rotary shaft, a loosely-mounted shaft adjacent to said pinion and provided with a fixed gear in mesh 25 with said pinion, a star-cam keyed on said loosely-mounted shaft, a trip-lever pivoted to a fixed point and engaged by said star-cam, a tilting lever fulcrumed near its center and provided with a pile-warp rod, and a tension- 30 spring connecting the free end of the first lever with the end of the second lever remote from the pile-warp rod, whereby the continuous motion of the crank-shaft may intermittently vibrate the pile-warp rod, substantially 35 as described.

6. The combination, with the intermittent-motion mechanism and the pile-warp let-off and the take-up motions, all substantially as de-

scribed, of the rotary shaft L, provided with the gear K', worm w, and gear g, gearing with 40 said motions, respectively, substantially as herein described.

7. The combination of the crank-shaft I, having the spline s, the hand-wheel H, provided with boss h, having the notch t and the pin h' thereon, said wheel mounted on said shaft and sliding thereon over the fixed spline, and provided with the presser-spring i, the suitably-mounted shaft K, provided with the fixed star-wheel k and bevel v, the shaft L, 50 having the wheel l' and provided with bevel K', the pinion g, and the worm w, the shaft r, provided with the gear-wheel g' and star-cam g², the pivoted lever g⁴, provided with roller g³, the tension-spring g⁶, the tilting-lever g⁷, 55 provided with the pile-rod G, the oppositely-rotating delivery-rollers a' and a², provided with the gears J and l, and the tension-roller a, provided with the swinging arms, all constructed and operating substantially as and 60 for the purpose described.

8. The combination of the crank-shaft I, having the spline s, the hand-wheel H, provided with the boss h, having the notch and pin, the shaft K, provided with the star-wheel 65 k and gear-wheel v, the shaft L, provided with the gear-wheel K' and the gear-wheel g, the shaft r, provided with gear-wheel g' and the star-cam g², the pivoted lever g⁴, provided with roller g³, the tension-spring g⁶, and the tilting-lever g⁷, provided with the pile-rod G, substantially as herein described.
